ALBERT LAWRENCE SAUNDERS AND ALBERT HENGESBACH, OF WEYBURN,
SASKATCHEWAN, CANADA.

SHARPENING DEVICE FOR DISKS OF DISK HARROWS.

1,170,114.

Specification of Letters Patent.

Patented Feb. 1, 1916.

Application filed September 7, 1915. Serial No. 49,409.

To all whom it may concern:

Be it known that we, ALBERT LAWRENCE SAUNDERS and ALBERT HENGESBACH, both of the city of Weyburn, in the Province of 55 Saskatchewan, Canada, have invented certain new and useful Improvements in Sharpening Devices for Disks of Disk Harrows, of which the following is a specification.

This invention relates to devices for 10 sharpening the disks of disk harrows and plows, and our object is to devise a tool which may be used to sharpen the disks while they are in place on the harrow.

We attain our object by providing a lever 15 arm with a fork adapted to embrace the axles of the harrow and with a hardened steel blade adjustable to and from the fork, and shaped to engage the disk edge.

The tool is constructed in detail and operated substantially as hereinafter described 20 and illustrated in the accompanying drawings in which—

Figure 1 is a front elevation of a disk harrow illustrating the method of using our 25 sharpening device. Fig. 2 a front elevation of part of the sharpening device on an enlarged scale, and Fig. 3 a side elevation of the same parts.

In the drawings like numerals of reference 30 indicate corresponding parts in the different figures.

This device is formed as a lever arm having the fork 1 formed at its lower end. The upper end 2 is shaped for insertion in a 35 wooden handle 3, in which it is secured by means of the bolts 4. Between the ends of the lever arm is formed the longitudinal slot 5.

6 is a sharpener blade, which is secured 40 to the lever arm by means of the clamping bolt 7 passing through a hole in the sharpener blade and through the slot 5. With this arrangement the sharpener blade can be adjusted to suit the diameter of the disk 45 being operated on, and the angle of the sharpening blade to the lever arm can be varied as may be necessary. The lower edge of the sharpener blade is serrated as shown, the serrations being the same at each side of 50 the center of the disk so that the tool may

be used equally as well on the left hand as on the right hand disks.

The device is used by placing the fork over the axle of the harrow, with the sharpening blade engaging the edge of a disk as shown 55 in Fig. 1. By applying lateral pressure to the lever arm the blade is applied to the edge of the disk at the proper angle and sharpening takes place as the disk is rotated by the forward movement of the harrow. 60 To resist the upward strain on the device due to the pressure of the inclined edges of the serrations on the disks we provide the fork with a pivoted latch 8 which may be clamped below the harrow axle by means of 65 the bolt 9 with which the notch 10 in the latch 8 engages. The serrations are such that if necessary the front of the edge as well as the back of the edge of the knife may be contacted with the scraper. 70

This device is effective in use and satisfactorily accomplishes the object of our invention as set out in the preamble to this specification.

What we claim as our invention is:— 75

1. A disk sharpening device comprising a lever arm having a fork integrally formed at one end in alignment with the lever; and a sharpener blade secured to the lever transversely thereof and adapted to be engaged 80 with the edge of the disk.

2. A disk sharpening device comprising a lever arm provided with means of engagement with an axle; and a transverse sharpener blade secured to said arm transversely 85 thereof, the edge of said blade nearest the fork and at each side of the lever being serrated, substantially as shown and described.

3. A disk sharpening device comprising a 90 lever arm having a fork formed at one end and a longitudinal slot formed therein between the ends; and a transverse sharpener blade secured to said arm by means of a clamping bolt passing through the blade and 95 through said slot, the edge of said blade nearest the fork being serrated substantially as shown and described.

4. A disk sharpening device comprising a 100 lever arm having a fork integrally formed

at one end in alinement with the lever; a sharpener blade secured to the lever transversely thereof and adapted to be engaged with the edge of the disk; a latch pivoted on one arm of the fork; and means for releasably securing the latch to the other arm of the fork.

Signed at the city of Weyburn this 17th

day of August, 1915, in the presence of the two undersigned witnesses.

ALBERT LAWRENCE SAUNDERS.
BERT HENGESBACH.
